PLASTER SUPPORT

Original Filed Feb. 9, 1923

UNITED STATES PATENT OFFICE

EDWARD SPENCER HALL, OF HIGHLANDS, NEW JERSEY, ASSIGNOR TO MITCHELL HOLDING CORPORATION, OF NEW YORK, N. Y., A CORPORATION

PLASTER SUPPORT

Continuation of application Serial No. 618,008, filed February 9, 1923. This application filed January 20, 1925, Serial No. 3,605, and in Canada June 25, 1923.

This invention relates to a plaster support.

An object of the invention is to provide a plaster support which will hold the soft plaster applied thereto and which will reinforce this plaster after it has hardened.

Another object is to provide a support with reinforcing bars which will become substantially entirely imbedded in the plaster and which will reinforce and brace the plaster

10 both vertically and transversely.

Another object is to provide a plaster support with transverse reinforcing bars which will keep the plaster from slippage or displacement.

15 Another object is to provide a plaster support with reinforcing bars which will hold the soft plaster from outward displacement.

Another object is to provide a plaster support which, with the plaster, will produce a 20 damp-proof, fireproof, vermin-proof, heat insulating and sound deadening wall.

Other objects of the invention will become apparent from the embodiment hereinafter set forth.

25 According to the invention as it is herein set forth, it comprises a corrugated board having on the face thereof vertical and transverse reinforcing members or bars which become entirely embedded within the plaster 30 substantially throughout the length thereof and thereby reinforce the plaster both vertically and transversely.

The vertical reinforcing bars are fastened to the board at the crest of the ridges and span the furrows between the same.

35 The transverse reinforcing bars are arranged in the furrows and held in position therein by the vertical reinforcing bars.

40 The soft plaster is applied to the corrugated board and over the vertical and transverse reinforcing bars and thereby these bars become substantially embedded in the plaster and reinforce it both vertically and transversely.

45 The corrugated board and the transverse reinforcing bars both support the soft plaster vertically and thereby keep it from slipping downward. The vertical and transverse reinforcing bars hold the soft plaster

on the board and keep it from outward displacement.

The transverse reinforcing bars are ordinarily flat metal strips which have on each edge thereof alternate upward and downward flanges, the flanges on one side being arranged to overlap the flanges on the other side so as to reinforce the bar and give it rigidity.

55 These flanges, particularly the outer flanges, serve to hold the soft plaster from outward displacement.

The invention embodied in the plaster support herein set forth for the purpose of explanation is susceptible of various obvious 60 modifications.

This application is a continuation of application filed February 9, 1923, Serial No. 618,008, and a continuation in part of application filed May 27, 1922, Serial No. 564,081. 65

70 The accompanying drawings illustrate the plaster support.

Fig. 1 is a front elevation.

Fig. 2 is a rear elevation within the area bounded by the line X—X of Fig. 1.

Fig. 3 is a vertical sectional view on the line 3—3 of Fig. 2 showing the support with the plaster applied.

Fig. 4 is a sectional view on the line 4—4 of Fig. 2 showing the way the vertical reinforcing wires or bars are fastened to the board by the wire on the back thereof.

Fig. 5 is a view in perspective of the transverse reinforcing bars.

The plaster support comprises, in general, 85 a corrugated board 1 having on the face thereof vertical reinforcing wires or bars 2 and transverse reinforcing bars 3.

The corrugated board is ordinarily made 90 of fibrous material, which is coated, impregnated or otherwise treated with asphaltum or other material which will make it damp-proof, vermin-proof and preserve the same.

The vertical reinforcing wires rest upon 95 the ridges of the corrugated board and span the furrows between the same.

They are held in place by holding wires 4 arranged on the back of the corrugated board in alignment therewith and having loops 5 100 which pass through the crests of the ridges

and are hooked or pass over the vertical reinforcing wires.

These holding wires, in addition to fastening the vertical reinforcing wires and the 5 corrugated board together, further serve to brace and reinforce the corrugated board.

The transverse reinforcing bars are ordinarily arranged in alternate furrows and retained therein by the vertical reinforcing 10 bars.

They are preferably in the form of a flat metal strip 6 which has alternate upward and downward flanges 7 on the inner and outer edges thereof, with the flanges on one 15 edge overlapping the flanges on the other edge.

They are of such width as to support the plaster vertically and are braced, reinforced and given rigidity by the flanges thereof.

20 The plaster support is ordinarily fastened in position on the wall or ceiling by staples 8 which pass over both the vertical wires and transverse bars at points where they cross.

The transverse bars with the alternate upward and downward flanges expand and contract in such way as not to cause line cracks.

25 The corrugated board is preferably flush with the transverse bars at one end and projects beyond these bars at the other end so that adjacent boards may be overlapped and the transverse bars brought together.

As the vertical and transverse reinforcing bars are arranged throughout their length 30 on the front of the corrugated board, they become substantially entirely embedded within the plaster and thereby firmly reinforce the plaster both vertically and transversely and produce a very strong wall.

35 The ridges and the transverse reinforcing bars so support the soft plaster that it will not slip downward before it hardens.

The soft plaster is firmly held on the board 40 by the transverse bars, particularly the outer flanges thereof, which is very advantageous 45 in further increasing the hold of the plaster on a ceiling.

It is further held on the board by adhesion therewith.

Of course, the plaster support herein explained 50 for the purpose of illustration may be modified in various ways and still be within the purview of the claims hereof.

Claims—

55 1. A plaster support comprising a corrugated board having vertical and transverse reinforcing members on the front thereof to be substantially entirely embedded in the plaster, the vertical reinforcing members being fastened to the crests of the ridges and the transverse reinforcing members being arranged in the furrows between the ridges.

60 2. A plaster support comprising a corrugated board having vertical and transverse reinforcing members on the front thereof to be substantially entirely embedded in the

plaster, the vertical reinforcing members being fastened to the crests of the ridges and the transverse reinforcing members being arranged in the furrows between the ridges and behind the vertical reinforcing members, said transverse reinforcing members being formed 70 from strips of sufficient width to support the plastic plaster and having a flange to hold the plaster from outward displacement.

75 3. A plaster support comprising a corrugated board having vertical and transverse reinforcing members arranged upon the front thereof, the vertical members being fastened to the ridges at the crests thereof by wires arranged in alignment therewith along the back of said board and passing therethrough at the crests of said ridges, the transverse reinforcing members being held in place upon the front of said board by the vertical reinforcing members.

80 4. A plaster support comprising a corrugated board having vertical and transverse reinforcing members arranged upon the front thereof to be substantially entirely embedded 85 in the plaster, the vertical reinforcing members being fastened to the crests of the ridges and the transverse reinforcing members being held in the furrows between the ridges by the said vertical reinforcing members, said transverse members being formed from strips of sufficient width to support the plastic plaster and having flanges to hold the plaster from outward displacement.

90 5. A plaster support comprising a corrugated board having vertical wires and transverse bars on the front thereof to be substantially entirely embedded in the plaster, the vertical wires being arranged to engage the board at the crests of the ridges thereof and being held in place thereon by wires arranged 95 in alignment therewith on the back of the board and passing through the board and about the vertical wires at the crests of the ridges, and said transverse bars being arranged in the furrows between the ridges of the board and held therein by those portions 100 of the vertical wires which span the furrows.

105 6. A plaster support comprising a corrugated board having vertical and transverse members on the front thereof, the vertical members engaging the board at the crests of the ridges thereof and spanning the furrows between the ridges, the transverse members being arranged in the furrows between the ridges and behind the vertical members, wires arranged on the back of the board in alignment with the said vertical members and passing through the board and around the vertical members at the crests of the ridges, and said transverse members having a flange 110 to hold the plaster from outward displacement.

115 7. A plaster support comprising a board, means arranged upon the front of said board to reinforce hard plaster and shaped to re- 120

tain and support soft plaster upon said board, and means arranged upon the front and back of said board and connected to each other at intervals to hold said board and aforesaid means together.

8. A plaster support comprising a board, means arranged upon the front of said board to reinforce hard plaster and shaped to retain and support soft plaster upon said board, and parallel longitudinal back members arranged upon the back of said board and connected to said means at intervals to keep the same in place.

9. A plaster support comprising a board, means arranged upon the front of said board to retain and support soft plaster, parallel longitudinal front members arranged upon the front of said board to keep said means in place, and parallel longitudinal back members arranged upon the back of said board in alignment with said front members and connected to said front members at intervals.

10. A plaster support comprising a board, parallel transverse front members arranged upon the front of said board to retain and support soft plaster, parallel longitudinal front members arranged upon the front of said board to keep said transverse members in place, and parallel longitudinal back members arranged upon the back of said board in alignment with said front members and connected to said front members at intervals.

11. A plaster support comprising a corrugated board, means arranged in the furrows upon the front of said board to reinforce hard plaster and shaped to retain and support soft plaster upon said board, and means arranged upon the front and back of said board and connected to each other at intervals to hold said board and aforesaid means together.

12. A plaster support comprising a corrugated board having transverse ridges and furrows, means arranged in the furrows upon the front of said board to retain and support soft plaster, and parallel longitudinal front and back members arranged in alignment and connected to each other at intervals to hold said board and means together.

50 13. A plaster support comprising a corrugated board having transverse ridges and furrows, transverse members arranged in the furrows upon the front of said board, and parallel longitudinal front and back members arranged in alignment with each other and connected at intervals to hold said board and members between the same.

60 14. A plaster support comprising a corrugated board having transverse ridges and furrows, parallel longitudinal front members arranged in the furrows upon the front of said board, and parallel longitudinal back members arranged upon the back of said board in alignment with said front members and connected to said front members at the

crest of the ridges upon the front of said board.

70 15. A plaster support comprising a corrugated board having transverse ridges and furrows, means upon the front of said board to retain and support soft plaster, parallel longitudinal front members arranged upon the front of said board to keep said means in place, and parallel longitudinal back members arranged upon the back of said board in alignment with said front members and connected to said front members at the crest of the ridges upon the front of said board.

75 16. A plaster support comprising a corrugated board having transverse ridges and furrows, transverse members arranged in furrows upon the front of said board to retain and support soft plaster, parallel longitudinal front members arranged upon the front of said board to keep said transverse members in place, and parallel longitudinal back members arranged upon the back of said board in alignment with said front members and connected to said front members at the crest of the ridges upon the front of said board.

80 17. A plaster support comprising a board, means arranged upon the front of said board to hold and reinforce plaster, and parallel members arranged upon the back of said board and having loops formed therein to hold said means in place.

85 18. A plaster support comprising a board, parallel longitudinal front members arranged upon the front of said board, and parallel longitudinal back members arranged upon the back of said board in alignment with said front members and having loops formed therein and connected to said front members.

90 19. A plaster support comprising a board, means arranged upon the front of said board to hold and reinforce plaster, parallel longitudinal front members arranged upon the front of said board to keep said means in place, and parallel longitudinal back members arranged upon the back of said board in alignment with said front members and having loops formed therein and connected to said front members.

95 20. A plaster support comprising a board, parallel transverse members arranged upon the front of said board to hold and reinforce plaster, parallel longitudinal front members arranged upon the front of said board to keep said transverse members in place, and parallel longitudinal back members arranged upon the back of said board in alignment with said front members and having loops formed therein and connected to said front members.

100 21. A plaster support comprising a corrugated board, parallel longitudinal front members arranged upon the front of said board, and parallel longitudinal back members arranged upon the back of said board in alignment with

ment with said front members and having loops formed therein and connected to said front members.

22. A plaster support comprising a corrugated board, means arranged upon the front of said board to hold and reinforce plaster, and parallel longitudinal members arranged upon the back of said board and having loops formed therein to hold said means in place.

23. A plaster support comprising a corrugated board having transverse ridges and furrows, transverse members arranged in furrows upon the front of said board to hold and reinforce plaster, parallel longitudinal front members arranged upon the front of said board to keep said transverse members in place, and parallel longitudinal back members arranged upon the back of said board in alignment with said front members and having loops formed therein and connected to said front members.

24. A plaster support, comprising a corrugated board, reinforcing bars arranged within the furrows upon the front side of said board, reinforcing members arranged upon the front of said board transversely of said furrows, and means passing through the crests of the ridges between said furrows to fasten said members to said board.

25. A plaster support, comprising a corrugated board, reinforcing bars arranged within the furrows upon the front side of said board and having flanges to hold plaster against outward displacement, reinforcing members arranged upon the front of said board transversely of said furrows, and means passing through the crests of the ridges between said furrows to fasten said members to said board.

26. A plaster support, comprising a corrugated board, reinforcing bars arranged within the furrows upon the front side of said board, and having flanges upon the front and rear edges thereof, reinforcing members arranged upon the front of said board transversely of said furrows, and means passing through the crests of the ridges between said furrows to fasten said members to said board.

50 In witness whereof, I have hereunto subscribed my name this 15th day of January, 1925.

EDWARD SPENCER HALL.
